Filed Feb. 23, 1967, Ser. No. 5,920

Term of patent 14 years

(Cl. D58—17)

FIG. 1 is an exploded top perspective view of a covered pail showing our new design;

FIG. 2 is a bottom perspective view with the lid omitted and showing the side opposite that seen in FIG. 1;

FIG. 3 is an enlarged fragmentary sectional view taken as on the line 3—3 and of FIG. 1; and

FIG. 4 is an enlarged fragmentary sectional view taken on the line 4—4 of FIG. 2.

The dominant features of the design reside in the portions shown in full lines.

We claim:

The ornamental design for a covered pail, as shown and described.
